IRONER SHOE AND CONTROL DEVICE

Joseph A. Briggs, Park Ridge, Ill., assignor of
one-half to Donald P. Mossman, Sr., and one-
half to John E. Mossman

Application January 20, 1945, Serial No. 573,749

4 Claims. (Cl. 219—19)

1

The present invention relates to the shoes of ironing machines. It is the principal purpose of this invention to provide more uniform and accurate heating control of the ironer shoe.

In ironer shoes as they are now constructed, the main part of the shoe is a heavy metal bar which in cross section is curved to provide a concave surface for engaging the ironer drum. The side edges of this bar are usually curved up away from the concave surface and the heating element by which heat is applied to the bar is arranged along the convex surface of the bar between the turned up side edges. According to my invention I use two heating elements along the back of the shoe and press them into position by employing a sub-shoe that presents a concave surface toward the main shoe. I utilize this sub-shoe in two ways to improve the operation and control of the heating means for the shoe. According to my invention the sub-shoe is so constructed as to have considerably less rigidity than the main shoe and it is given a greater overall curvature than the main shoe so that when it is applied to the main shoe over the heating element it can be placed under a tension that will guarantee adequate tight engagement of the heating element with the main shoe. This construction of the sub-shoe enables me also to use it as a supporting means for a control switch limiting the temperature of the main shoe.

It is a further purpose of my invention to provide in an ironer shoe a novel circuit control mechanism responsive to the temperature of the iron for breaking the circuit to the heating elements. The construction of the circuit control being such that the heat responsive element is free of the circuit, and therefore, uninfluenced by the heating effect of current flowing in the circuit. By this construction it is possible also to avoid the damaging effects of the high temperatures of the main shoe to current carrying parts of the control. The construction also enables me to place the heat responsive element in the most favorable position for response to the temperature of the main shoe.

The nature and advantages of my invention will appear more fully from the following description and accompanying drawings wherein a preferred form of the invention is disclosed. It should be understood however, that the drawings and description are illustrative only and are not to be taken as limiting the invention except insofar as it is limited by the claims.

In the drawings:

Figure 1 is a plan view of an ironer shoe embodying my invention;

2

Figure 2 is an enlarged sectional view taken through the shoe on the line 2—2 of Figure 1;

Figure 3 is an enlarged fragmentary sectional view taken on the line 3—3 of Figure 1;

Figure 4 is a fragmentary plan view of a slightly modified form of the invention; and

Figure 5 is a sectional view taken on the line 5—5 of Figure 4.

Referring now to the drawings, the ironer shoe of the present invention is made up of a main shoe 10 which comprises a bar of rather heavy gauge metal. This shoe is curved so as to present a concave surface 11 toward the drum or roll portion 12 of the ironer. The bar has its side edges 13 and 14 turned up away from the roller 12. The side edges 13 and 14 give rigidity to the bar 10.

In order to heat the main shoe, I provide thereon two heater elements 15 and 16. These heater elements are placed upon insulating strips 17 and 18 that are laid against the convex back of the main shoe 10. A suitable insulating material for this purpose is mica. The heating elements are covered with insulating sheets 19 and 20 and the assemblies of the heating elements with their insulating sheets are pressed against the main shoe by a sub-shoe 21. This sub-shoe extends the full length of the main shoe as illustrated in Figure 1 of the drawings. It carries two ears 22 and 23 by which the ironer shoe may be mounted. The sub-shoe is provided with a raised central portion 24. This central portion terminates just short of the ends of the sub-shoe so as to leave two end portions 25 and 26 to make a close fit all the way across the ends of the main shoe.

In a device of this character, I find that the heating of the main shoe may be made more uniform by insuring adequate and uniform engagement of the heater assemblies with the back of the main shoe. According to my invention, I so construct the sub-shoe 21 as to cause it to follow the shape of the main shoe when it is under compression and thus guarantee uniform engagement of the heating units with the main shoe. I make the sub-shoe 21 with a somewhat greater curvature between its side edges than is found in the corresponding part of the main shoe. This greater curvature is indicated by the dotted line 21a in Figure 2 of the drawings. The sub-shoe is made of material having at least some resiliency. It is also made of lighter or more yielding material than the main shoe 10. The two shoes are secured together by a series of spaced studs 27, spaced lengthwise along the main shoe and extending outwardly through the raised central portion 24 of the sub-shoe where

they receive washers 28 and nuts 29. By tightening the nuts 29 I draw the central portions of the two shoes toward each other. Because the main shoe is most rigid at its side edges and the sub-shoe is most rigid at the raised central portion 24, I can bring the heating elements under substantially uniform pressure from side to side and cause them to tightly engage the back of the main shoe.

I also utilize the sub-shoe 21 as a means for mounting a control switch that is adapted to open the circuit for the heating coils 15 and 16 when the temperature of the main shoe reaches a pre-determined level. One of the features of this part of my invention is a construction whereby the heat responsive element is entirely free of the control circuit so that the current flowing through the heaters only affects the temperature control element through the heat imparted to the main shoe.

Referring now to Figures 2 and 3, I show a shaft 30 mounted in the raised portion 24 of the sub-shoe 21. This shaft serves to pivot a lever 31. The lever 31 is bent into substantial U shape as shown and pivotally supports a second lever 32 which is also U shape. A pivot pin 33 connects the levers 31 and 32, the pin being located at the free end of the lever 31 and intermediate the ends of the lever 32. The lever 32 carries a wiring terminal 34 and a switch contact 35 at the end thereof most remote from the shaft 30. One of the leads 36 supplying current to the heating elements 15 and 16 extends into the space between the raised portion 24 of the sub-shoe 21 and the back of the main shoe for mounting on the terminal 34. The sub-shoe has an opening 37 cut out to provide for making connections. At one edge of the opening 37 I mount a bar 38. The bar 38 carries a contact 39 and a wiring terminal 40 to which a lead 41 is mounted. As illustrated in Figure 3 the contacts and terminals are insulated from their respective supports 32 and 33 in accordance with well known practice.

The bar 38 has a spring 42 secured to its free end and this spring is also connected to the lever 32 between the pivot pin 33 and the contact carrying end of the lever 32. The spring is under sufficient tension to maintain the contacts 35 and 39 in engagement. In order to separate the contacts, I provide a finger 43 on the lever 32 and I provide a bi-metallic heat responsive strip 44 on the main shoe 10. The strip 44 is secured at 45 to the main shoe. This securing may be accomplished in several ways. Wherever possible it is desirable to weld this strip to the main shoe since this gives a good heat conducting joint. A bar 46 may also be used across the secured end of the element 44 if desired. It will be noted that the element 44 is so positioned that it receives its heat directly from the main shoe 10, likewise the element is entirely free of the electrical circuit for supplying current to the heating elements 15 and 16. The element 44 when heated will swing up to engage the lever 32 and tend to move the finger 43 upward. In normal operation the spring 42 holds the parts in the position shown in Figure 3 with the lever 31 resting against the lower end of an adjusting screw 47. This adjusting screw can be moved up or down so as to change the normal resting position of the finger 43 with respect to the element 44. In this way the temperature of the main shoe 10 at which the current will cut off can be varied to suit the desired working conditions.

It will be noted from Figures 2 and 3 that actually contact elements 35 and 39 are spaced well away from the main shoe 10 so that they are not subjected to the intense heat of the ironer shoe. However, the more important fact is that the bi-metallic heat responsive element 44 is under no load whatsoever during the entire run of normal operation of the shoe. The element 44 is only subjected to mechanical stress when the shoe 10 gets hot enough to make it necessary to open the circuit by separating the contacts 35 and 39. This is a particular advantage in prolonging the life of the control element. It is also a particular advantage in maintaining the accuracy of the control. It is obvious that the control element cannot keep its accuracy as well when it is under strain or carrying current or both, as it can when during most of the time of operation it is under no mechanical strain and is carrying no current.

For some purposes it is desirable to have a less sensitive control and one which is not so expensive. Likewise, it is desirable to have a control where all of the parts are readily accessible for replacement. In Figures 4 and 5 of the drawings I illustrate a form of device wherein the sensitiveness shown in the controls of Figures 1 and 3 is somewhat sacrificed to provide a cheaper and more accessible control unit. In this form of the invention I mount a bi-metallic heat responsive element 48 on the raised portion 24 of the sub-shoe 21. The bi-metallic heating element 48 is mounted by a removable bolt 49, the head of which is formed in such fashion to hold the bar 48 in proper alignment lengthwise of the portion 24. A nut 50 is used to clamp the parts together. The bi-metallic element 48 has a contact engaging pin 51 at its free end. This pin extends through an aperture 37 provided in the part 24. There are two studs 52 and 53 mounted in the part 24 at opposite ends of the aperture 37. The stud 53 is apertured at its top end to receive a pivot pin 54 which mounts a bifurcate lever arm 55. The lever arm 55 has its free end also bifurcated at 56 as shown in Figure 4. This bifurcated end of the lever arm 55 extends over the stud 52 and rests upon a spring 57. The level of the lever arm 55 is controlled by an adjusting screw 58 that is threaded into the stud 52. The screw 58 has a head 59 thereon, the head 59 being of any suitable material but having a wear plate 60 which is adapted to engage rounded surfaces 61 provided on the lever arm 55.

The lever arm 55 carries the circuit control elements for controlling the supply of current to the heating elements 15 and 16 of the ironer shoe. One conducting strip 62 has a stationary contact 63 thereon. Another spring contact carrying strip 64 carries the other contact 65. The members 62 and 64 are carried by the lever 55 being mounted by suitable insulating members 66 and a screw 67 that threads into the lever 55.

In operation the device shown in Figures 4 and 5 responds generally to the heat of the shoe, but does not show the sensitiveness of the form of device shown in Figures 1 and 3. In this form of the invention the element 48 normally lies flat against the under surfaces of the member 21. It has sufficient strength and resiliency to hold the contacts 63 and 65 closed against the light pressure of the spring 64. Since the sole function of the member 64 is to carry current and since gravity would pull it away from the member 62, it can be made quite light to thus avoid any substantial load on the bi-metallic element 48. When

the temperature of the bi-metallic element 48 increases, it will tend to overcome the pressure of the bimetallic element upward to keep the contacts 63 and 65 closed and eventually will so change the shape of the bi-metallic element as to permit the contacts to separate. This breaks the supply of current to the ironer shoe. It will be evident from the foregoing description that the device shown in Figures 4 and 5 does not either have the sensitivity or the freedom from strain that the heat responsive mechanism in the main form of the invention has. However, the bi-metallic element 48 like the bi-metallic element 44 is entirely free of the electrical circuit. The head portion 51a of the member 51 is of insulation.

It is believed that the foregoing description and the accompanying drawings will enable those skilled in the art to practice the invention and to appreciate the advantages of the novel features disclosed.

Having thus described my invention, I claim:

1. An ironer shoe comprising a main shoe bar, electrical heating means resting on the back side of said bar, and a sub-shoe having a raised central channel portion extending lengthwise over the main shoe bar and having side portions pressing the electrical heating means against the bar, the sub-shoe and the main shoe having means connecting said central channel portion and the main shoe bar to clamp them together, both of said shoes being curved transversely, with the sub-shoe having a greater initial curvature whereby to cause the side edges of the sub-shoe to act as fulcrum points when the shoes are drawn together, the main shoe having its side edges turned up whereby to provide the greatest rigidity at the side edges of the main shoe.

2. An ironer shoe comprising a main shoe bar, electrical heating means resting on the back side of said bar, and a sub-shoe pressing the electrical heating means against the bar, the sub-shoe and the main shoe having means cooperating to clamp them together, both of said shoes being curved transversely, with the sub-shoe having a greater initial curvature whereby to cause the side edges of the sub-shoe to act as fulcrum points when the shoes are drawn together, the main shoe having its side edges turned up whereby to provide the greatest rigidity at the side edges of the main shoe, and the sub-shoe having its central portion raised to provide a substantial U shape channel part, thereby giving the central portion of the sub-shoe the greatest rigidity.

3. An ironer shoe comprising a main shoe bar, electrical heating means resting on the back side of said bar, and a sub-shoe having a raised central channel portion extending lengthwise over the main shoe bar and having side portions pressing the electrical heating means against the bar, the sub-shoe and the main shoe having means connecting said central channel portion and the main shoe bar to clamp them together, both of said shoes being curved transversely, with the sub-shoe having a greater initial curvature whereby to cause the side edges of the sub-shoe to act as fulcrum points when the shoes are drawn together, and the sub-shoe being substantially less rigid than the main shoe in the parts thereof covering the heater elements.

4. An ironer shoe comprising a main shoe bar, electrical heating means resting on the back side of said bar, and a sub-shoe having a raised central channel portion extending lengthwise over the main shoe bar and having side portions pressing the electrical heating means against the bar, the sub-shoe and the main shoe having means connecting said central channel portion and the main shoe bar to clamp them together, both of said shoes being curved transversely, with the sub-shoe having a greater initial curvature whereby to cause the side edges of the sub-shoe to act as fulcrum points when the shoes are drawn together, said sub-shoe having circuit controlling means for the heating elements mounted in said channel portion, and the main shoe having a heat responsive means thereon positioned to actuate the circuit control means on the sub-shoe.

JOSEPH A. BRIGGS.
